Inventor:
Henry H. Merrell.
by

Frank L. Clark
Atty.

UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

CHANELER.

Application filed March 25, 1922. Serial No. 546,921.

- My invention relates to channelers and more particularly to means for controlling the feeding of channeling mechanisms of the multiple standard type.
- 5 An object of my invention is to provide an improved channeling mechanism. Another object of my invention is to provide an improved channeling mechanism of the multiple standard, multiple-tool type in which the channeling devices on either standard may be controlled independently of those on the other, or in which both may be readily controlled simultaneously, the control mechanism being of an improved nature whereby it is readily accessible from different positions and readily controllable by the operator. Other objects and advantages of my invention will hereinafter more fully appear.
- 10 In the accompanying drawings, I have shown for purposes of illustration one form which my invention may assume in practice.
- In these drawings,—
- Fig. 1 is a view mainly in end elevation, 25 but with parts broken away to show details of construction.
- Fig. 2 is an enlarged detail view showing parts as cut on the section line 2—2 of Fig. 3.
- 30 Fig. 3 is a plan view of a portion of the channeling mechanism, parts being broken away above the section line 3—3 of Fig. 1.
- Fig. 4 is section on the line 4—4 of Fig. 1.
- Fig. 5 is a view approximately on the 35 line 5—5 of Fig. 3, but with most of the operating mechanism shown in elevation instead of in section.
- The improved channeling mechanism which constitutes the illustrative embodiment of my invention includes a main frame 1 which is supported upon wheels 2 mounted on axles 3 extending across the frame at opposite ends thereof. The machine is adapted to be fed by means of transmission 40 mechanism generally indicated by 4 driven as desired by the operator by a reversible motor 5 under the control of suitable control mechanism 6, 7. As my invention relates more particularly to the means for controlling the raising and lowering of the channeling device and to the general arrangement of the parts, the mechanism so far described will not be more fully set forth.
- 45 Extending longitudinally of the frame 1 is a bar 8 upon which there are adjustably clamped as at 9 (Fig. 1) standards 10, which standards form guiding means for channeler mechanisms generally indicated by 11. These channeler mechanisms include motors 12 driving, by a suitable gearing of which a portion is shown at 13, a suitable crank shaft 14 which by its rotation reciprocates a cylinder 15 in which a piston 16 connected by a rod 17 to a suitable gang 18 is mounted, the cylinder 15 and gang 18 being suitably guided by means carried in the standards 10. The channeling mechanisms are each supported on frames 19 and by feeding the frames up and down the standards, the 50 tools may be withdrawn or lowered with respect to the bottom of the cut as may be necessary. A feed screw 20 suitably supported by a thrust bearing 21 is carried near the base of the guides on the standards 10, this feed screw being rotated by a worm wheel 22 keyed thereto, which worm wheel is driven by a worm 23 which is in turn driven by a chain 24 and mechanism later more fully described. The feed screw 20 55 engages with a nut 25 secured on the frame 19 and rotation of the screw 20 will cause the channeling mechanism to move upward or downward in the standards dependent upon the direction of rotation of the screw 20. It will be understood that each of the channeling mechanisms cooperating with the standards is provided with one of these feed screws and, as will be observed from Fig. 3, the driving chains 24 for the worms 23 pass around driving sprockets 26 and 27 which are secured by split collars 28 to sleeves 29 and 30, respectively, which sleeves are journaled upon opposite ends of a shaft 31 which is provided with a journal as indicated at 32, the sleeves also being journaled exteriorly in bearings 33 and 34 fixed to the frame 1. The shaft 31 carries keyed thereto a beveled gear 35 which is driven by a beveled pinion 36 mounted on the opposite end of the armature shaft of the motor 5 from that which drives the truck propelling mechanism. There are also keyed to the shaft 31 a pair of sleeve members 37 and 38, which members are provided with braking surfaces 39. Carried by the sleeve members 29 and 30 are clutch carrying members 40 of well known commercial construction, these including clutch bands 41 which may be tightened by oscillation of 60

shafts 42 which are provided with operating levers 43. The levers 43 may be swung in planes transverse to the shaft 31 by cams 44 and 45 which are longitudinally slideable 5 upon the peripheries of the sleeves 29 and 30 respectively.

For the purpose of moving the cams 44 and 45 longitudinally, I have arranged in suitable guides 46 and 47 respectively below 10 and to one side, and above, the shaft 31, longitudinally movable operating slide rods 48 and 49, these being provided with shippers 50 and 51, respectively, operative to move the cams 44 and 45, and the slide rods 48 15 and 49 are provided with laterally projecting studs 52 and 53 whereby they may be engaged and moved by means which will now be described. It should first be noted, however, that movements of the rods 48 and 20 49 in opposite directions will cause them to effect similar functions, i. e., relatively opposite movements of the rods will produce simultaneous application of the brake bands 39 and simultaneous release thereof.

25 Fixed to the frame are suitable hangers 54 and 55, there being journaled in the hanger 54 a hollow shaft member 56 which carries at one end thereof a socket member 57 and at the opposite end thereof a second 30 socket member 58 with an oppositely extending arm 59 which receives in a slot 60 therein the pin 52. Extending through the shaft member 56 and also through the hanger 55 is a smaller shaft 61 at whose end adjacent 35 the socket member 57 there is carried a socket member 62 and at whose opposite end is a second socket member 63 with a relatively similarly directed operating arm 64 which receives in a slot 65 therein the pin 53. Adapted to cooperate with the 40 socket members 57 and 58 and 62 and 63, respectively, are manual control levers 67 and 68 which, as will be apparent from Figure 1, are so shaped that they approach each 45 other at their upper ends when in sockets 58 and 63 whereby they may be readily grasped by the operator with the use of only one hand, while by reason of the parallel disposition of the sockets 57 and 62 50 they can be similarly grasped when in the latter sockets.

From the foregoing description the mode of operation of my improved mechanism will be readily apparent. It will be remembered that the motor 5 is reversible. Accordingly, as the motor 5 is driven in one direction and the cam members 44 and 45 are moved to cause the clutch bands 41 to tighten upon the braking surfaces 39, both 55 channeling mechanisms will be raised or lowered simultaneously. If one of the levers 67 or 68 is operated to move its corresponding clutch operating cam, but one of the channeling mechanisms will be moved. 60 65 It will therefore be apparent that by ma-

nipulation of the levers 67 and 68 and the control mechanism for the motor 5, the channeling mechanisms can be simultaneously raised, simultaneously lowered, or moved independently of each other in either 70 direction. By reason of the fact that the handles whether in the sockets 58 and 63 or 57 and 62 are so close as to be readily grasped simultaneously by the operator when using but one hand, it will be apparent 75 that, should it become desirable in an emergency to move the two devices in either direction very quickly, this can be done with ease and certainty.

While I have in this application specifically described one form which my invention may assume in practice, it will be understood that this form of the same is shown for purposes of illustration and that the invention may be modified and embodied in various other forms without departing from 85 its spirit or the scope of the appended claims.

What I claim as new and desire to secure by Letters Patent is:

1. In a channeling mechanism, a main 90 frame, a pair of standards thereon, normally independently or simultaneously operable channeling devices adjustably mounted on said standards and each having usual channeling steels, and means for adjusting said channeling devices in a direction longitudinally of said steels including control levers separately or simultaneously operable by a single hand of the operator.

2. In a channeling mechanism, a main 100 frame, a pair of standards thereon at opposite ends of said frame, normally independently or simultaneously operable channeling devices adjustably mounted on said standards and each having usual channeling 105 steels, and means for adjusting singly or simultaneously said channeling devices in a direction longitudinally of said steels including control levers separately or simultaneously operable by a single hand of the 110 operator.

3. In a channeling mechanism, a main frame, a pair of standards thereon, channeling devices guided on said standards and each having usual channeling steels, and means for normally simultaneously or independently feeding said devices in a direction longitudinally of said steels including a plurality of feeding mechanisms, a common driving shaft therefor, and means 115 for connecting said feeding mechanisms in operative relation to said driving shaft including a reversibly rotatable driving shaft, clutch mechanisms thereon, parallel clutch operating members, and clutch operating 120 means separately or simultaneously operable by but one hand of the operator for actuating said members.

4. In a channeling mechanism, a main frame, a pair of standards thereon, chan- 130

In testimony whereof I affix my signature.
HENRY H. MERCER.
